BEACH CHAIR

Harry Kleinberg, Brooklyn, N. Y.

Application October 18, 1940, Serial No. 361,746

5 Claims. (Cl. 155—153)

This invention relates generally to chair construction, and more particularly to an improved beach or lawn chair.

My improved beach chair comprises a main frame adapted to rest on the ground; and a back frame, pivotally mounted on the main frame and covered with suitable material to provide a back rest. A seat is stretched between a cross-bar on the back frame and one arranged on arms pivoted in the main frame. When the chair is set up for use the seat section is located somewhat above the main frame, above the ground. Novel seat supporting levers associated with the pivoted arms come into action to fixedly support the seat when in the set up condition.

The back section is arranged to be folded onto the main frame. When my novel beach chair is folded, its thickness does not exceed the thickness of the main frame. The back frame as well as the seat supporting levers and arms are housed well within the main frame. The particular construction of the levers connected with the seat supporting arms makes the folding and the setting-up of the chair particularly simple. In its folded state the improved chair can be easily carried or stored, requiring a minimum of space.

It is accordingly an object of the present invention to provide an improved collapsible beach chair of light weight, compact, strong, and durable construction.

Another object of the invention is to provide a beach chair of the type referred to, which is very flat and compact when folded up.

A further object of the invention is to provide an improved collapsible chair which can be readily folded and unfolded by simple swinging of its back frame.

Still another object of the invention is to provide an improved beach chair having a guided seat supporting lever construction, facilitating folding and unfolding of the chair.

These and further objects of the invention will become more evident in the following description of a preferred embodiment illustrated in the drawings, wherein:

Fig. 1 is a perspective view showing the chair set up for use.

Fig. 2 is a section substantially on the line 2—2 of Fig. 1 on an enlarged scale, with some parts being broken away.

Fig. 3 is a section along the line 3—3 of Fig. 2, on an enlarged scale, showing a detail of the chair construction.

Figs. 4 and 5 are enlarged end views showing

the seat supporting lever in different positions with respect to the seat.

Fig. 6 is a cross-section on the line 6—6 of Fig. 5, showing details of mounting of the seat supporting cross-rod.

Fig. 7 is a perspective view of the chair in its folded up position.

Referring more particularly to the drawings, my improved chair comprises a main frame generally designated at 10, and a back frame generally designated at 11. The main frame has two side bars 12, 13 which are connected by the substantially flat cross-bar 14 mounted at the forward ends thereof. Back frame 11 comprises two side bars 15, 16 pivotally mounted by bolts on main frame side bars 12, 13, respectively. Back frame side bars 15 and 16 are connected by cross bar 18.

As clearly shown in Fig. 1, cross bar 18 is secured to the rear side of side bars 15 and 16 and protrudes a certain distance on both sides thereof for the purpose to be described. Two hooked bars 20, 20 are pivotally connected at 21 to respective bars 15, 16 of frame 11, and preferably consist of flat metal members. Bars 20, 20 each have a slot 19 adapted to engage a bolt 22 provided at the rear end of frame side bars 12, 13.

Cross rod 24 extends between back frame side bars 15, 16 and is arranged at some distance above main frame 10 so that the seat section supported thereby may be situated above ground. Since there are no legs on the beach chair of the invention in which main frame 10 rests directly on the ground, this factor is important to the comfort of the user.

Two arms 25, 25 are individually pivotally connected at 23 to main frame side bars 12, 13. The ends of arms 25 support cross rod 26. Two levers 27, 27 are respectively pivoted at 29 on main frame side bars 12, 13, between main frame 10 and arms 25. Two connecting levers 28, 28 are pivotally mounted at 30 and 31 between arms 25 and levers 27.

A sheet 32 of canvas or other suitable flexible material is supported by cross rods 24 and 26 to constitute the seat section. Seat 32 is secured on its supporting cross rods 24 and 26 by means of hems 33 or other suitable fastening method. Another sheet 34, which may also consist of canvas or any other suitable fabric, is fastened or tacked onto frame side bars 15 and 16, as indicated at 35 in Fig. 7.

The manner of pivotally mounting back frame 11 on main frame 10 is shown in Fig. 3. A spacer

ring 36 is provided between main frame side bar 13 and back frame bar 16. Another spacer 36 is arranged between main frame side bar 12 and back frame bar 15. Each of the rings 36, 36 is faced with two metal washers 37, 37 to reduce the bearing friction. This arrangement enables the housing of bars 20, as well as levers 27, between back frame 11 and main frame 10 when the chair is folded up.

Each of the levers 27, 27 has a projecting arc-shaped end portion 40 as clearly shown in Figs. 4 and 5. As shown more particularly in Fig. 6, seat supporting cross rod 26 is secured to pivotal arms 25 by means of a counter-sunk screw 41. Protective metal rings 42 are secured at the ends of cross rod 26. When the arms 25, 25 are swung in a counterclockwise direction from the folded-up position or from the semi-folded position of Fig. 5, to the set-up position of Fig. 4, the end portion 40 of each lever 27 bears against its associated ring 42 on cross rod 26. The position of Fig. 4 corresponds to the chair as set-up ready for use.

The weight of the person seated on seat 32 tends to pull cross rod 26 toward back frame 11. Arms 25 are prevented to rotate further in the counterclockwise direction by the supporting and abutting action of levers, 27, 27. At the same time, opposite cross rod 24 is impelled to the right, in the direction towards the front of the seat. This pull is taken up by links 20, 20 hooked onto bolts 22, 22 in the frame 10. Thus, links 20, 20 and levers 27, 27 support the seat of the chair in the set-up position of Fig. 1, against the weight of a person seated thereon.

In order to fold the beach chair, links 20, 20 are unhooked from bolts 22, and back frame 11 is swung in a clockwise direction until it is flush with main frame 10. Links 20, 20 are then respectively located between side bars 12, 15 and side bars 13, 16. Cross rod 26 is then rotated in a clockwise direction until it presses against main frame cross bar 14, as shown in Fig. 7. Cross bar 14 thus serves as a stop for cross rod 26. Levers 27 follow arms 25 due to their interconnection by links 28.

Levers 27 are thereupon arranged between main frame side bar 12 and back frame side bar 15, as well as between main frame side bar 13 and back frame side bar 16. The protruding portion of back frame cross bar 18 presses against the upper surface of main frame side bars 12 and 13, thus preventing further rotation thereof. The length of back frame 11 is such that, when folded, back frame cross bar 18 does not extend as far as seat supporting cross rod 26.

The back frame 11, as well as seat supporting cross rod 26 with its arms 25 and levers 27 are thus housed well within main frame 10, in the folded up position of the chair. The combined thickness of an arm 25, a lever 27 and an associated connecting member 28 does not exceed the thickness of one spacer ring 36. Either of the two cross bars 14 and 18 may be used to grip the folded chair for carrying. By pressing cross bar 18 against main frame side bars 12 and 13, unfolding of the chair is prevented.

Various changes and modifications may be made to the details of construction of the invention without departing from the broader spirit and scope thereof, as set forth in the following claims.

I claim:

1. A chair of the character described comprising a main frame adapted to rest on the ground, a back frame pivotally connected near one end of said main frame and containing a first cross rod, means connecting the main frame and back frame for holding the latter at a predetermined angle to the former when erected, a pair of arms pivoted on opposite side of said main frame, a second cross rod spaced from said first cross rod and supported between the free ends of said arms, a seat of flexible material extending between said first and second cross rods, a pair of levers pivoted on said main frame adjacent each of said arms, the free ends of said levers projecting to bear against said second cross rod when it is swung above the plane of said main frame, and links pivotally joining the associated levers and arms, whereby said levers follow the swinging motion of said arms and second cross rod to support it in the upper position.

2. A chair of the character described comprising a main frame adapted to rest on the ground, a back section pivotally connected with and foldable into said main frame, a hooked connecting member for connecting said back section to said main frame at a predetermined angular relation thereto, a first cross rod extending across said section, a pair of arms pivoted on said main frame, a second cross rod spaced from said first cross rod and supported between the free ends of said arms, a flexible sheet fastened between said first and second cross rods to form a seat section, a pair of levers pivoted on said main frame, the free ends of said levers being arranged to bear against said second cross rod when it is swung out of the plane of said main frame, and two members pivotally connecting each of said arms with its associated lever whereby said levers follow the swinging motion when said arms and second cross rod are swung about.

3. A chair of the character described comprising a main frame adapted to rest on the ground, said main frame comprising two side bars and a connecting cross bar at one end of said side bars, a back section pivotally connected at the opposite end of said main frame embodying two side bars and a second cross bar, said section being foldable into said main frame, hooked means holding said section to said main frame in a predetermined extended relation, a first cross rod extending between said back frame side bars and arranged above the pivots thereof, a pair of arms pivoted on said main frame side bars, a second cross rod spaced from said first cross rod and supported between the free ends of said arms, a flexible seat fastened between said first and second cross rods, a lever pivoted on each of said main frame side bars, the free ends of said levers being adapted to bear against said second cross rod when it is swung out to above the plane of said main frame, links pivotally connecting each of said arms with one of said levers, said main frame cross bar serving as a stop for said second cross rod, the protruding ends of said back section cross bar bearing against said main frame side bars when the chair is in its folded up position.

4. A chair of the character described comprising a main frame adapted to rest on the ground, a back section pivotally connected with said main frame, hooked flat bar means pivotally mounted on said section and adapted to be hooked onto said main frame, a first cross rod on said section and arranged above the pivots thereof, a pair of arms pivoted on said main

frame, a second cross rod spaced from said first cross rod and supported between the free ends of said arms, flexible material fastened between said first and second cross rods to form a seat section, a pair of levers pivoted on said main frame between its arms and said back section, the free ends of said levers being arc-shaped and arranged to bear firmly against said second cross rod when it is swung above the plane of said main frame and against said levers, and links pivotally connecting each of said arms with one of said levers, whereby said levers follow the swinging motion of said arms and said second cross rod to firmly maintain the seat in the set-up position against said lever ends.

5. A chair of the character described comprising a main frame adapted to rest on the ground and including two side bars and a cross bar connecting the extreme ends thereof, a back section pivotally connected with said main frame comprising two side bars and a cross bar arranged at the ends thereof and protruding therefrom, a spacer ring arranged at the pivots between each of said section side bars and its adjacent main frame side bar, a hooked bar pivotally mounted on said backing frame and adapted to

be hooked onto said main frame when the back section is extended, a first cross rod extending between said section side bars and arranged above the pivots thereof, a pair of arms pivoted 5 on said main frame side bars, a second cross rod spaced from said first cross rod and supported between the free ends of said arms, flexible material fastened between said first and second cross rods to form a seat section, a pair of levers 10 pivoted on said main frame side bars between said arms and the back section, the free ends of said levers being arranged to abut said second cross rod when it is swung out of the plane of said main frame and against said lever, links 15 pivotally connecting each of said arms with its associated lever, said main frame cross bar serving as a stop for said second cross rod, the protruding ends of said back section cross bar bearing against said main frame side bars when 20 the chair is in its folded up position; said arms, levers and hook bar being arranged to fit into the space between said main frame side bars and said back section side bars when the chair is folded up.

HARRY KLEINBERG.
